(57) **CLAIM**

The ornamental design for a hat heat press as shown and described.

DESCRIPTION

FIG. 1 is a perspective view of a shell of hat heat press showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a perspective view of a main body of hat heat press showing my new design;

FIG. 10 is another perspective view thereof;

FIG. 11 is a front view thereof;

FIG. 12 is a back view thereof;

FIG. 13 is a left view thereof;

FIG. 14 is a right view thereof;

FIG. 15 is a top plan view thereof;

FIG. 16 is a bottom plan view thereof; and,

FIG. 17 is a perspective view of a hat heat press showing my new design, in a split state of use.

The broken lines depict portions of the hat heat press and form no part of the claimed design.
